CLAIM

The ornamental design for a file rack as shown and described.

DESCRIPTION

FIG. 1 is a perspective view of a file rack showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is the first partial enlarged view of FIG. 1 thereof; and,

FIG. 10 is the second partial enlarged view of FIG. 1 thereof. The dash-dot broken lines depict portions of the file rack that form no part of the claimed design. The dash-dot broken lines illustrate the bounds of the enlarged view and form no part of the claimed design.
